UNITED STATES PATENT OFFICE

WILLIAM A. RANKIN, OF ROCK ISLAND, ILLINOIS, ASSIGNOR TO BIRTMAN ELECTRIC COMPANY, OF CHICAGO, ILLINOIS, A CORPORATION OF ILLINOIS

SWIVEL BASE CONSTRUCTION

Application filed December 18, 1931. Serial No. 581,970.

This invention relates to improvements in swivel base construction. For the purpose of illustrating one use of my invention, I have shown the same incorporated in a swivel vise 5 or a vise with a swivel base. It is to be understood, however, that the invention is not limited to use with vises, but may be employed in connection with other machines, devices, and the like.

10 Heretofore, vises of the character referred to have lacked rigidity and firmness between the base and the body when clamped in position. This has been due to the ordinary two-point support (not considering the pivot) 15 which permitted a certain amount of rocking of the body. One of the features of my invention is the provision of a construction furnishing a three-point support, thus making the body firm, steady and rigid on the base in 20 any of its clamped positions.

A vise of the character referred to is provided with a base member and a body member pivotally mounted on the base, ordinarily by a screw or bolt in the center. A clamping 25 screw is arranged at one side. In the older constructions, when the clamping screw is screwed in against the base, the body rocks slightly on the pivot screw as a fulcrum and makes contact with the base at a point diametrically opposite the clamping screw. There is thus a two-point contact or support 30 (disregarding the pivot screw), namely, at the clamping screw and a point diametrically opposite. This two-point support permits a 35 slight rocking of the body on the base.

In the practice of my invention, I eliminate this two-point support and provide a three-point support instead. In one embodiment of the invention I accomplish this by recessing 40 the body through an arc of about 100° opposite the clamping screw, so that when the clamping screw is turned in against the base, the body will rock slightly and make contact with the base at two points instead of one, 45 these two points being separated about 100° and each being about 130° from the clamping screw. There will thus be a three-point support between the body and base giving a very firm, steady and rigid mounting in any 50 position of the body.

In another embodiment of the invention, I provide three bolts between the body and the base spaced substantially 120° apart about the pivot point. The base and body are slightly separated by a lug or shoulder 55 around the pivot. One of the bolts is adjustable; and when it is tightened, the base rocks on the lug drawing up the other two bolts, thus again giving a three-point support. 60

Other features and advantages of my invention will appear more fully as I proceed with my specification.

In those forms of device embodying the features of my invention shown in the accompanying drawings. 65

Figure 1 is a view in side elevation; Fig. 2 is a view taken as indicated by the line 2 of Fig. 1; Fig. 3 is a fragmentary view of the body and base in rear elevation; Fig. 4 70 is a view taken as indicated by the line 4 of Fig. 1; Fig. 5 is a view taken as indicated by the line 5 of Fig. 1; Fig. 6 is a view similar to Fig. 2 of a modified form showing a section taken as indicated by the line 6-6 of 75 Fig. 8; Fig. 7 is a view of the body looking upwardly; Fig. 8 is a view of the base looking downwardly; and Fig. 9 is a view showing a modified form of adjusting bolt. 80

As shown in the drawings, the vise includes 85 a circular base member 10 provided with the usual perforated ears 10^a permitting it to be fastened to any suitable support 11, as by the lag screws 12.

The top of the base 10 may be provided with notches or serrations 10^b to assist in holding the clamping screw in its desired location. 85

Numeral 13 indicates a circular body member pivotally mounted on the base 10 by the usual screw 14. Numeral 15 indicates the usual separating bushing member on the screw 14 to prevent the body 13 from being too closely drawn against the base 10 when the screw is tightened. In other words, there must be a slight play between the members 13 and 10 to permit rotation of the vise on the base when the clamping screw is loose. 95

The body member 13 supports the body 100

proper 16 of the vise and 17 indicates the usual movable jaw of the vise.

At one side of the swivel screw 14 the body member 13 is provided with the clamping or retaining screw 18 adapted to be screwed down against the base 10 to hold or support the vise in its clamped position. The lower end 18^a of the screw 18 is adapted to engage in the serrations 10^b.

10 The particular feature of my invention is the recessing of the underside of a portion of the periphery of the body member 13 opposite the clamping screw 18. Such recessing is clearly shown in Figs. 3 and 4, as indicated by 19. This recess extends through substantially 100° and terminates in shoulders 19^a, 19^b. When the clamping screw 18 is screwed in against the base 10, the body 13 rocks slightly on its pivotal mounting to cause the shoulders 19^a, 19^b to be brought into contact with the base. This will give three supporting points or retaining elements spaced about the axis of the pivot, said three points being the vertically adjustable clamping screw 18 and the other two, the shoulders 19^a, 19^b.

15 I shall now describe the form of invention embodied in the construction shown in Figs. 6, 7 and 8. As here shown, the body member is indicated by 113 and the base member, by 110. The body is pivotally mounted on the base by means of the depending pin 114. Numeral 115 indicates a shoulder or lug surrounding the pin 114 to space the body 113 a short distance from the base 110.

20 The base 110 is provided with a circular keyhole slot 120 accommodating the heads 121 of two supporting, retaining or clamping bolts 122 provided with nuts 123 above the body 113. There is also provided a third adjustable retaining, clamping or supporting bolt 122^a, the head 121^a of which also lies in the slot 120. The nut 123^a on this bolt is provided with a pin 123^b to permit ready adjustment of the same.

25 In the operation of the structure as shown in Figs. 6, 7 and 8, when the bolt 122^a is tightened, the body 113 rocks slightly on its pivotal mounting to cause the bolts 122 to tighten up. The three bolts are spaced substantially 120° apart and, consequently, this will give three supporting points spaced about the axis of the pivot, said three points being the three bolts.

30 In Fig. 9 I have shown another form of clamping screw that could be used instead of the clamping screw 18 of Fig. 2. As shown in Fig. 9, the clamping screw is indicated by 218 and instead of being threaded in the body member 213, the same goes through a plain hole. The member 213 is provided with a recess 213^a accommodating the nut 230. When the screw 218 is turned down, the nut 230 is held against rotation 35 by the walls of the recess 213^a and this causes

upward pressure against the member 213. It is understood, of course, that the lower end of the screw 218, as indicated by 218^a, engages a base member under it, as in Fig. 2.

35 While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

40 What I regard as new, and desire to secure by Letters Patent, is:

45 1. Swivel base construction, including; a base member; a body member pivotally mounted on the base member; and a clamping screw carried by one of said members, said member having a portion of its periphery recessed opposite said clamping screw whereby tightening of the clamping screw will cause engagement between said members at two points opposite said clamping screw.

50 2. Swivel base construction, including; a base member; a body member pivotally mounted on the base member; and a clamping screw carried by the body member, said body member having a portion of its periphery recessed opposite said clamping screw, whereby tightening of the clamping screw will cause contact of the body member with the base member at two points opposite said clamping screw.

55 3. Swivel base construction, including; a base member; a body member pivotally mounted on the base member and spaced therefrom around the pivotal mounting, said spacing imposing a limited zone of reaction; and three clamping bolts carried by one of said members and engaging the other, said bolts being spaced about the axis of the pivot and from and about said zone of reaction to the clamping stress, and one of the same being adjustable.

60 4. Swivel base construction, including; a base member; a body member rotatably mounted on the base member; and means for anchoring the body member against rotation, said means imposing a stress in one direction at one point, and a stress in the opposite direction at three separate points surrounding said first point.

65 In witness whereof, I have hereunto set my hand this 11th day of December, 1931.

WILLIAM A. RANKIN.
